FLUORESCENT LIGHT SOCKET

William E. McSween, Cleveland, Ohio

Application March 31, 1941, Serial No. 386,088

1 Claim. (Cl. 173—328)

This invention relates to electric light sockets and particularly to the type of socket used with a fluorescent lamp.

As conducive to a clearer understanding of this invention, it may be well to point out that tubular fluorescent lamps have sets of cathode and anode terminals at each end thereof, and that it is necessary to make electric contact with each set of terminals before the lamp will light. Heretofore, the lamp sockets used for each set of terminals were mounted apart and facing each other on a single bracket which was a little longer than the lamp bulb itself. The sockets were stationary and not movable with respect to each other. This restriction often limited the way the lamp could be mounted and it was never possible to mount a lamp of this type so that even, direct, and unobstructed illumination could be had for the entire peripheral area around the lamp. The long bracket or connector which extended lengthwise of the lamp and from one end thereof to the other, always obstructed the light rays at that side. Also, by some reason of the old method of rigidly mounting the sockets, the lamp terminals had to be engaged with the electric contacts in each socket by a radial application. In other words the two corresponding sockets had to have suitable aligned grooves which opened into their circumferential surfaces, and which could receive the sets of anode and cathode terminals simultaneously.

It is therefore the primary object of this invention to provide lamp sockets which will support fluorescent lamps of different lengths and which permits the mounting of such lamps in a manner which eliminates the necessity of intermediate adjacent parallel supports or direct and rigid connectors between the sockets at the ends of the lamps.

Another object is to provide a socket of the type mentioned which permits the lamp terminals to be engaged with or set longitudinally into the socket instead of laterally therewith.

Further object is to provide such socket with springs which engage the metal collars of the lamp and hold it firmly therein.

Still another object is to construct such socket so that the electric automatic heater switch may be replaced by a manually operated control switch.

These and other objects and advantages of the invention will become apparent from a study of the following description and claim together with the accompanying drawing in which like parts are designated by like reference characters and wherein:

Figure 1 is a comprehensive view of a number of fluorescent light sockets of this invention suspended on chains and supporting a series of lamps;

Figure 2 is an enlarged view of one of the sockets with a heater switch mounted thereon and also showing a part of a lamp;

Figure 3 is a view of the open end of the socket into which the lamp member is inserted;

Figure 4 is a view of the opposite end of the socket and which end receives the heater switch;

Figure 5 is a vertical sectional view of the socket taken along the lines and in the direction 10 of the arrows 5—5 of the Figure 3;

Figure 6 is a vertical sectional view of the same socket taken along the lines 6—6 of the Figure 5;

Figure 7 is a vertical sectional view of the same socket taken along the lines 7—7 of the Figure 5;

Figure 8 is a vertical sectional view of the same socket taken along the lines 8—8 of the Figure 6; and

Figure 9 is a horizontal sectional view taken along the line 9—9 of the Figure 5.

20 In the drawing, the Figure 1 shows a comprehensive view of a pair of sockets made in accordance with this invention and as they would appear suspended on chains and supporting a conventional tubular fluorescent light bulb. In this figure, the character 2 indicates a socket of this invention one of which has a special heater switch 20 attached thereto. Character 11 indicates the loop on the socket which engages the chain 12. The electric wires or conductors are indicated by the character 13.

Referring particularly to the Figure 2, the socket shown consists of two semi-tubular metal shells 21 and 22 which are held together by means of the diametric screw 26 and which are referred to in the claim as, a split tubular shell member. The top shell 21 is engaged with the bottom shell 22 at the separable joint 23.

The Figure 3 which is a right end view of the socket illustrated in the Figure 2 shows the top and bottom shells 21 and 22 joined together at 23. Just inside the end opening four small wire springs 40 are fastened to the two shells to form, when the shells are in an assembled relation, an octagonal holding means. The wire springs 40 are fastened to the respective shells at the points 41 by either a weld or solder. The intermediate portions are relatively loose and are free to engage the small circumferential groove 42 on each end of the lamp member 15.

The Figure 4 is a left end view of the socket only which is shown in the Figure 2. The details of the heater switch 20 are not shown as it, by itself, forms no part of this invention. The Figure 4 therefore, shows the fibre disk 58 which closes the end of the socket and in which there are two arcuate slots 59. The grooved terminals or contact members 57 of the heater switch project through the slots 59 and engage the spring 60 clamps 53 inside of the socket. The pair of

spring clamps 53 are eccentrically shaped pieces of spring metal which co-act and tightly engage the two grooved and aligned terminals 57 on the heater switch 20. Each clamp of the pair is so shaped that it contacts the side surface of the terminal 57 when the heater switch 20 is inserted in the socket 44 and when the terminals are turned slightly in the arcuate slots 59.

The sectional view of the socket, shown in the Figure 5, illustrates how the threaded loop 11 is held in rigid contact with the top shell 21 by means of the threaded and flanged bushing 28 that extends through the aligned openings 27 and 45. The top shell 21 has a threaded hole 27 therein to accommodate the threaded bushing 28. Near the opening 27, there is still another hole 24 which is threaded so as to engage the threaded end of the screw 26 which extends diametrically through the socket members and holds the top and bottom members together. It also has the springs 40 arranged to form an octagonal collar portion for retaining an end of the fluorescent lamp.

The top inner portion of the socket 2 is made of a fibre block or other dielectric material and is herein referred to as a case member 29. This block 29 has a curved surface to correspond with and to neatly fit the inner wall of the top shell 21. It also has a flat surface, a portion of which is cut away to provide room for the bushing 28. The opening through which the electric wire 13 passes is indicated by the character 45 and is radially aligned with the opening 27 in the top shell portion. The clip members 34 which are made of metal are fastened to the case member 29 on each side of the opening 45 by means of the screws 35. Each of the clip members 34 have bifurcated ends 36 which are tensioned so as to grip the electrical terminals 16 of the lamp members 15. The fibre disk or washer 38 which is mounted in front of the clips 34 and slightly to the rear of the springs 40 has two openings or parallel slotted channels 39 which provide entrance means or passage ways for the electrical terminal 16.

The opposite end of the socket is similarly provided with a pair of clamp members 51 which are attached to the dielectric case member 29 by means of the screws 52. Each of the clamp members 51 are provided with an eccentric arm 53 which is tensioned and shaped to engage the grooved terminals 57 of the heater switch 20 when they are properly inserted and turned slightly in the opening 44.

The bottom case member 30 is shaped very much like the upper case member 29. It is also provided with a diametric hole 32 for the screw 26 and in addition has portions cut away at 54 and 55 to provide for the extension of the bifurcated clips 36, which are engageable with the lamp terminals and with the eccentric arms or clamps 53 which are engageable with the heater switch terminals. The top and bottom case members 29 and 30 are also referred to as a split dielectric body portion.

In order to complete the electric circuit for the lamps 15 when the heater switch 20 is used, there must be a connection between one of the clip members 34 and one of the clamp members 51. This is provided for by the insertion of a small bridge or connector 61 which is held in place by the screws 35 and 52 respectively.

In use, the socket may be assembled completely

before the lamp 15 and the heater switch 20 are engaged therewith. In that case the lamp 15 is inserted longitudinally into the opening 43 so that the groove 42 engages the springs 40 and the electrical terminal 16 engaged the clips 36 simultaneously. When the socket is partly assembled the lamp can be made to engage the socket in a lateral fashion. That is, the electrical terminals are passed through the grooves 39 and engaged with the clips 36 at the openings 31. The shell member 22 together with the lower spring members 40 are then applied and fastened in place by the screw 26. The electric connections, of course, are easily made when the lower shell is loosened and separated from the top portions. The openings 33 and 45 provide ample space for the necessary wires. If the socket 2 is to be used as the second of the pair, that is without the heater switch 20, then the opening 44 provided for the heater switch is simply plugged up with a piece of dielectric material or is left open as desired. Inasmuch as there are many different ways in which this socket and the fixture may be wired, the details of the wiring plan are not shown herein. However, for the sake of clarity, it may be mentioned that the conventional transformer which is generally used in connection with tubular fluorescent lamps, may be concealed in the ceiling canopy of the fixture, which incidentally is not shown herein because it constitutes no part of the instant invention and its use is well known to the art.

It is now clear that the sockets described accomplish the objects originally set forth and further have advantages which are not obtainable in any of the prior art sockets of this type. While the invention has been disclosed in its preferred form, it is to be understood that the embodiment of the invention as described and illustrated herein is not to be considered in a limiting sense as there are many other forms or modifications of the invention which are also considered to be within the scope of the appended claim.

I claim:

A lamp socket of the type used for fluorescent lamps having electric terminals and an auxiliary heater switch thereon, comprising in combination, a split tubular shell member having openings at oppositely disposed ends thereof and including a split dielectric body portion between the said openings, the said shell member and body portion having aligned radially extending openings between the ends thereof for receiving electric conductors, the said shell member also having resilient collar portions mounted thereon adjacent to one end of the body portion and engageable with the fluorescent lamp, a pair of bifurcated clip members electrically engageable with the said lamp terminals and mounted on the said body portion adjacent to the said collar portions and facing one of the aforesaid openings, and a pair of co-acting clamp members mounted on the opposite end of the body portion and adjacent to the other one of the said openings and aligned with the aforesaid pair of clip members, the said clamp members being engageable with the said heater switch terminals, one of the said clamp members having means thereon extending through the body member making electrical connection with the bifurcated clip member opposite thereto.

WILLIAM E. MCSWEEN.
